(57) **CLAIM**

The ornamental design for a post part for a dental implant, as shown and described.

DESCRIPTION

This application is related to U.S. patent application Ser. No. 29/553,912 filed Feb. 5, 2016, entitled “Root Part for a Dental Implant,” U.S. patent application Ser. No. 29/553,886 filed Feb. 5, 2016, entitled “Post Part for a Dental Implant,” U.S. patent application Ser. No. 29/553,881 filed Feb. 5, 2016, entitled “Post Part for a Dental Implant,” and U.S. patent application Ser. No. 29/553,896 filed Feb. 5, 2016, entitled “Root Part for a Dental Implant,” which are incorporated by reference herein in their entirety.

FIG. 1 is a perspective view of a post part for a dental implant showing my new design;

FIG. 2 is a side view thereof;

FIG. 3 is a side view thereof; and,

FIG. 4 is a side view thereof.

The broken line showing is included for the purpose of illustrating unclaimed subject matter and forms no part of the claimed design.
